UNITED STATES PATENT OFFICE.

FRANK A. HURLBUT, OF KANSAS CITY, MISSOURI.

THERMOSTATIC CONTROL FOR COOLING MEDIUMS.

1,348,420.

Specification of Letters Patent.

Patented Aug. 3, 1920.

Application filed November 13, 1918. Serial No. 262,354.

To all whom it may concern:

Be it known that I, FRANK A. HURLBUT, a citizen of the United States, residing at Kansas City, in the county of Jackson, State 5 of Missouri, have invented certain new and useful Improvements in Thermostatic Control for Cooling Mediums, of which the following is a full and exact specification.

The present invention relates to liquid 10 circulating devices for use in connection with heated surfaces, for keeping down the temperature of such surfaces, and is particularly useful in connection with the water tubes or casings employed in furnace wall 15 constructions, although not confined solely to such use. One of the objects of the invention, therefore, is to devise a cooling device provided with a circulating medium for cooling purposes, together with means 20 for regulating the circulation of the said medium in accordance with the changes of temperature therein.

It is also an object to construct a cooling 25 device adapted to maintain a circulating cooling medium in contact with the heated surface and under a given pressure, and provided with means acting automatically to regulate the outflow from the device in accordance with the temperature of said 30 medium, for the purpose of maintaining a given substantially constant temperature at the surface which is subjected to the heat.

For carrying out the invention a construction has been devised which comprises 35 a casing for containing the cooling medium and having suitable inlet and outlet points, and thermostatic means governing by temperature changes in the medium and acting to regulate the valve which controls the outlet from the casing.

With these general objects in view, the invention will now be described with reference to the accompanying drawing illustrating 45 one form of construction which has been devised for embodying the improvements, after which those features and combinations deemed to be novel will be set forth and defined in the appended claims.

50 In the drawing—

Figure 1 is a view in longitudinal section illustrating a water back construction for furnace walls, arranged in accordance with the present invention;

55 Fig. 2 is a vertical section, on an enlarged scale, showing the parts at the right end of Fig. 1;

Fig. 3 is a vertical section on the line III—III of Fig. 2; and

Fig. 4 is a fragmentary vertical section of 60 a furnace bridge wall construction showing the arrangement of the water-back member with reference to said wall.

Referring to the drawing in detail, this 65 illustrates the circulating member for the cooling medium as comprising an outer tubular water casing 2 adapted to be mounted at any desired point in the furnace wall,—Fig. 4 illustrating the mode of locating it in what is known as the bridge-wall 70 3. Within this casing 2 is mounted a feed water tube 4 extending axially through the casing 2 and provided at its outer end with a feed water pipe 6 adapted to be connected with any suitable source of water supply, or other cooling medium, preferably under suitable pressure. This feed water tube 4 is also fitted with a series of baffle elements 8 for the purpose of directing the water flow outward and effecting a relatively faster rate 75 of flow along the inner face of the outer casing than past the outer face of the feed tube, as explained in my Patent 1,269,083, issued June 11, 1918.

The water or other circulating medium is 80 conducted from the casing 2 by way of ports 10 provided through the head 12 of the casing and through a plate 14 and the valve casing 16, secured to the head 12 by means of bolts 18 and fitted with gaskets 20 as 85 shown in Fig. 2. Secured centrally to the plate 14 is a thermostatic element comprising 90 a tube 22 projecting a suitable distance within the casing 2 and provided with any preferred type of thermo-responsive medium for responding to temperature changes in the cooling medium and transmitting a corresponding action to a flexible diaphragm 24 clamped between the plate 14 and the valve casing 16 opposite the mouth of the tube 22. In register with the mouth of said tube 22 the valve casing 16 is formed with 95 a piston passage 26 for accommodating a piston member 28 which is mounted with its inner face in engagement with said diaphragm 24, the opposite face of said piston being exposed to the pressure of the liquid 100 emerging through the outlet ports 10. The piston 28 is connected by a stem 30 with a valve 32, which is secured by adjustable 105 threaded engagement with said stem and operates slidingly within a sleeve 34 fitted within the valve casing 16 and having outlet

110

ports 36 in communication with the outlet passage 38 provided with the pipe connection 40. A cap 42, having the vent 44, is fitted on the other end of the sleeve 34, is 5 whereby access may be had to the valve 32 for adjustment of the same in order to vary the point of cut-off to suit the working conditions of the device.

With the cooling medium supplied through 10 the connection 6 to the feed tube 4 at a constant rate or pressure, and with the valve 32 properly adjusted, it will be apparent that if the temperature of the cooling medium begins to rise above a certain point 15 the thermostatic element will be affected, the medium within the tube 22 expanding thereby actuating the diaphragm 24. In the normal position of the valve 32 (*i. e.*, more or less nearly closed), the pressure on the 20 outer face of the piston 28 substantially balances the pull exerted by the valve 32 and the pressure exerted by the thermostatic element at that temperature at which it is desired to maintain the cooling medium, but the action of the thermostatic element increases the pressure on the adjacent face of the piston, with the result 25 that the latter is moved in a direction to open the valve 32, thereby permitting some 30 of the water to leave the casing 2 and additional water to enter the same through the feed tube 4. This will of course act to check the rise in temperature, and as this 35 becomes normal the pressure on the inner face of the piston diminishes, due to contraction in the medium within the thermostatic tube, and said pressure will diminish until the piston has receded sufficiently to restore the valve 32 to its original 40 position. This original position of the valve 32 may of course be such as to leave the outlet ports normally slightly open so as to permit a certain degree of movement of the cooling medium at all times, and the 45 thermostatic control will then act to increase or decrease the flow in accordance with the temperature changes taking place in the outgoing water.

It will thus be seen that a simple, efficient 50 and compact arrangement and construction have been devised for carrying out the purposes of the invention, the valve action being at all times automatic and dependent upon the temperature of the cooling me-

dium as it leaves the device and serving 55 to maintain said cooling medium at a substantially constant temperature by regulating the flow in accordance with any change taking place in the temperature of the medium in the vicinity of the outlet from the 60 casing. While the foregoing illustrates what is now deemed to constitute the preferred form of embodiment of the improvements, the right is reserved to all such formal changes or modifications as may fairly 65 fall within the scope of the appended claims.

Claims:

1. A cooling device for heated surfaces, comprising a casing arranged to maintain 70 a liquid cooling medium in contact with a heated surface and under suitable pressure, said casing being provided with an outlet valve, and thermostatic means including a piston member connected with said valve 75 and having one of its faces exposed to the liquid as it approaches said valve, and a thermostatic element projecting within said casing and mounted in engagement with the opposite face of said piston member. 80

2. A cooling device for heated surfaces, comprising a casing arranged to maintain a liquid cooling medium in contact with a heated surface, said casing being provided with a valve for regulating the flow of 85 said medium through the casing, a piston member connected to said valve and having one of its faces exposed to said medium, and a thermostatic element mounted in said medium and in engagement with the opposite 90 face of said piston, whereby said valve is actuated in accordance with the temperature changes in said medium.

3. A water back construction for furnaces comprising a water casing provided 95 with a feed tube and an outlet valve, a piston operatively connected with said valve and having one of its faces exposed to the water pressure in said casing, and a thermostatic element carried within the casing 100 and mounted in operative relation to the opposite face of said piston, whereby said valve is actuated in accordance with the temperature changes in the water contained in said casing. 105

In witness whereof I hereto affix my signature.

FRANK A. HURLBUT.
